UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed October 3, 1925. Serial No. 60,190.

This invention relates to interponent or shield devices for typewriting machines and methods of using same, for preventing certain characters typed on a work-sheet from 5 being carbon-copied on an underlying record-sheet.

Many business firms have their checks and drafts arranged in sheet form for conveniently typing the payees' names and amounts 10 of the checks and making a record of the checks on an underlying record-sheet at the same time. It is usual for check register or record sheets to bear only the payee's name and the numerical amount of a check both in 15 a single line. To save space, it is desirable to have the lines of record data of several checks spaced much nearer each other on a record-sheet than they are on the usual check-sheet.

20 To these ends, provision is made in the present invention, of a paper chute or table mounted on a typewriter carriage and arranged with forwardly-projecting side flanges positioned apart approximately the 25 width of a sheet of checks. On each side of the table may be positioned a usual upper feed-roll of an Underwood typewriting machine. There is further provided a thin interponent or shield which may consist of 30 a rectangular cardboard strip having two narrow transverse slots extending from a long edge of the strip to within a short distance of the opposite side and positioned so that the shield may lie close against the table body with said slots engaging around said flanges; the closed ends of the slots engaging under the lower ends of the flanges, and the lower edge of the strip coming a short distance above the printing line.

40 A check-sheet overlying a wider record-sheet interleaved with carbon may be inserted from the rear around the platen; the check-sheet and carbon being passed in front of the table and the record-sheet behind it 45 and under the feed-rolls at the sides of the table. The shield may be pushed at will below the printing line to prevent characters typed on a check-sheet in front of the table from being carbon-copied on the record-sheet. A feature of the invention is an arrangement for raising the shield by line-spacing the work-sheets. By releasing the usual lower feed-rolls, the check-sheet may 50 be advanced while the record-sheet is held stationary by the upper paper feed-rolls.

This permits the second and additional checks of the check-sheet to be conveniently brought to printing position, during the stationary condition of the record-sheet.

Other features and advantages will hereinafter appear. 60

In the accompanying drawings,

Figure 1 is a fragmentary perspective view of the carriage of an Underwood typewriting machine, having my invention applied thereto, and showing a work-sheet in operative position, overlying a record-sheet interleaved with carbon. 65

Figure 2 is a fragmentary cross-sectional view of the same. 70

Figure 3 is a fragmentary front view of the same, showing the work-sheet advanced a short distance around the platen from the position of the sheet in Figure 1. 75

Figure 4 is a fragmentary front view of the same, showing the work-sheet advanced for printing a second line of characters thereon; the shield being lowered behind the second line.

Figure 5 is a diagrammatic view of a sheet or web of bank check slips. 80

A typewriter platen 10 on a shaft 11 mounted in carriage side frames 12 may have line-spacing means including a finger-wheel 13 and a ratchet-wheel 14, the latter 85 operated by a finger-piece mechanism, not shown. Two feed-rolls 17 engaging against the upper side of the platen 10 are carried by fingers 18 fastened to the arms 19, the latter being slidably and pivotally 90 mounted on a platen-carriage-rod 20. Feed-rolls 21 and 22 are mounted on feed-roll rods, not shown, and are arranged to be thrown against or away from the lower side of the platen 10 by means, not shown. A 95 paper-table 23 may have an apron extension 24 under the platen. The above-described parts may be the same as on an Underwood typewriting machine.

A paper table or chute 30, having two 100 forwardly-extending flanges 31, arranged for serving as side gages for work-sheets, may be supported by two arms 32 fast on side frames 12, so that the lower edge 33 of the table may be in close proximity to the platen, say about 45° above the printing line. Back or body portions 34 of the table may be slightly inclined rearwardly. 105

A rectangular interponent or shield 35 made preferably of relatively hard flexible 110

cardboard has two narrow slots 36 extending transversely from its top edge to within a short distance of its lower edge 35^a; providing a pair of parallel vertical tongues 35^b, 5 35^b, which slots are spaced apart a distance that permits the shield to lie close to the front face of the table 30, and substantially tangent to the platen 10 at the printing line with the slots 36 engaging around the flanges 10 31. In the assembled position on the table the closed ends of the slots 36 are below the lower extremities of the flanges 31, which thus limit the upward movement of the shield. Of course, the shield could also be 15 made higher and have the slots closed above as at the bottom in order to increase its durability and allow its inversion.

A plurality of bank checks 40^a, 40^b, etc., may be fastened one below another along 20 perforated lines 41, to form a sheet 42 having a width slightly less than the distance between the flanges 31. For conveniently writing data on the checks and making a condensed record of them at the same time, 25 the check-sheet 42 with a wider underlying record-sheet 43 and an interleaved carbon-sheet 44 may be inserted around the platen 10 from the rear, in the usual way. The three sheets may be advanced together as 30 far as the lower edge 35^a of the shield 35. There the check-sheet 42 and the carbon-sheet 44 will be passed in front of the shield 35 and advanced to bring the first or leading check 40^a in position for typing the payee's 35 name and the numerical amount of the check. The record-sheet will pass below and behind the shield and under the feed-rolls 17 positioned at either side of the paper table 30. In this position, the lower edge 35^a of the 40 shield may be held by friction between the work-sheets and the shield far enough above the printing line, as indicated by a type 50, to permit characters typed on a check-sheet to be carbon-copied on the record-sheet (see 45 Figures 1 and 2). The payee's name and the numerical amount of the first check may be typed in one line, as usual. The check, carbon and record sheets may now be line-spaced together to bring the check 40^a in 55 position for writing the amount of it in words below the payee's name. The lower edge 35^a of the shield 35 may be pushed down below the printing line (see Figure 4). After writing the amount of the check in 60 words, which the shield prevents being carbon-copied, the carriage may be moved to the right by the carriage finger-piece, not shown, and the platen line-spaced thereby as usual in an Underwood typewriter. The 65 platen 10 may be further line-spaced by manipulation in the usual way. The lower portion of the shield 35, at the beginning of these line-spacing operations, is held tightly between the carbon-sheet 44 and the record-sheet 43 and may be moved upwardly above

the printing line by friction of the moving sheets. The feed-rolls 21 and 22 may now be thrown off, and the check-sheet pulled ahead to bring the second check 40^b to proper position for having its payee's name and the 70 numerical amount typed as previously done on the first check 40^a. The record-sheet 43 is held against movement by the feed-roll 17 while the second sheet is advanced. For holding the check-sheet 42 closely against 75 the face of the shield 35, to increase the friction between the two, a finger-piece 54, more fully described in the patent granted to me March 18, 1924, No. 1,487,671, may be used. Checks may be severed from the sheet 80 or web 42 when they have been typed, and advanced above the paper-table or after the sheet has been removed from the machine and the checks have been dated and signed.

It may sometimes be desirable to withdraw 85 the shield from the printing line without line-spacing the record and check sheets. In such a case, it is but necessary to seize the end tongues 35^b, 35^b of the shield and thereby carefully draw the shield upward until 90 the bottoms of the slots engage the table-flanges, as already mentioned. The tongues may thus be considered as integral handles for the shield, in addition to their other office of assisting to guide the shield by their 95 inner edges engaging the table-flanges.

By the above-described means and the method of using the same, a greater number of checks can be recorded on a sheet, than if the record-sheet and check-sheet were advanced around the platen together in the usual way. Although described in connection with the typing of checks and similar instruments, it can be readily seen that the herein-described devices may be advanced 105 advantageously used for other work.

Variations may be resorted to within the scope of the invention, and portions of the improvements may be used without others.

Having thus described my invention, I 110 claim:

1. In a typewriting machine, the combination with a carriage and a platen, of a paper-table mounted on said carriage above said platen and having forwardly-extending 115 side flanges, and a type-blow-receiving shield movable up and down against the face of said table and extending downwardly substantially tangent to said platen at the printing line thereof, said shield having two 120 narrow, open guide-slots extending downwardly from its top edge and arranged to engage around said flanges from below.

2. A typewriting machine including the combination with a rotatable platen and a work-table disposed above the same, of a shield slidable on said table and arranged tangent to the platen, means on said table to guide said shield in advance movement, and means on said shield below the leading 130

edge thereof for engaging said table to stop said shield in movement a distance beyond the printing line.

3. A typewriting machine including the combination with a rotatable platen and a work-table disposed above the same, of a shield slidable on said table and arranged tangent to the platen, means on said table to guide said shield in advance movement, and projections on said shield between the leading and rear edges thereof for engaging said table to stop said shield in movement a distance beyond the printing line.

4. A typewriting machine including the combination with a rotatable platen and a work-table disposed above the same, of a shield slidable on said table and arranged tangent to the platen, there being side flanges on said table to guide said shield in advance movement, and integral side tongues on said shield for engaging the lower extremities of said table-flanges to stop said shield in a position beyond the printing line.

5. A typewriting machine including the combination with a rotatable platen and a work-table disposed above the same, of a shield slidable on said table and arranged tangent to the platen and having integral tongues projecting upwardly to serve as handles whereby to withdraw said shield from the printing line, there being means to guide said shield in movement on said table.

6. In a typewriting machine, the combination with a carriage and a platen, of a paper-table mounted on said carriage above said platen, there being forward projections on said table, and a type-blow-receiving shield movable along the face of said table and extending downwardly substantially tangent to said platen at the printing line thereof, said shield having two relatively narrow slots disposed in parallel relation to the sides of said shield and arranged to engage said table-projections.
